CURLING IRON

Filed March 29, 1924

2 Sheets-Sheet 2

UNITED STATES PATENT OFFICE.

JERROL E. LAWTON, OF BUFFALO, NEW YORK.

CURLING IRON.

Application filed March 29, 1924. Serial No. 702,943.

To all whom it may concern:

Be it known that I, JERROL E. LAWTON, a citizen of the United States, residing at Buffalo, in the county of Erie and State of New York, have invented new and useful Improvements in Curling Irons, of which the following is a specification.

This invention relates to improvements in hair-curling irons and has for an object 10 the provision of an electrically heated iron by means of which a Marcel wave may be easily and conveniently produced. More specifically stated, the invention aims to provide an iron, the jaws of which are 15 transversely curved to produce a wave in one direction and are also capable of relative longitudinal movement to produce a wave in another direction.

With the above and other objects in view, 20 the invention further includes the following novel features and details of construction, to be hereinafter more fully described, illustrated in the accompanying drawings and pointed out in the appended claim.

25 In the drawings:—

Figure 1 is an elevation of the invention.

Figure 2 is a section on the line 2—2 of Figure 1.

Figure 3 is a like view on the line 3—3 30 of Figure 1.

Figure 4 is a plan view of the iron.

Figure 5 is a fragmentary longitudinal section.

Figure 6 is a similar view showing a different position of the relatively movable jaw and also showing by dotted lines the position of the relatively movable jaw when the jaws are open.

Referring to the drawings in detail 40 wherein like characters of reference denote corresponding parts, the iron as shown comprises a pair of relatively movable members, one of said members comprising a hollow shank 10, a handle 11 and a jaw 12, 45 the latter being hereinafter referred to as the rigid jaw in that it is rigid with the handle 11 and the latter is the main handle of the device.

This rigid jaw is transversely curved as 50 shown in Figure 2 of the drawings and provides a longitudinally disposed seat 13 in one face thereof and spaced channels 14 in the opposite face, the said channels accommodating tubular casings 15 which are 55 suitably secured in place and which contain electric heating elements 16. Current

may be supplied to the heating elements 16 through conductors 17 which extend through the tubular shank 10 and through the handle 11 for connection with a suitable 60 source of current. The jaw 12 is provided upon opposite sides of the seat 13 with a row of spaced teeth 18 between which a quantity of hair is placed so that the hair 65 will lie across the seat 13.

The other upper edge of the device comprises a shank 19 which carries at one end a handle 20 and at its opposite end a jaw 21 and as this member is mounted for pivotal and longitudinal movement, the jaw 70 21 will be hereinafter referred to as the relatively movable jaw. This jaw 21 is transversely curved and is adapted to be positioned within the seat 13 and is provided with a row of spaced teeth 22, these 75 teeth as well as the teeth 18 being preferably struck from the material of which the jaws are made. The teeth 22 are disposed in an opposite direction from the teeth 18 and the hair which is positioned across the 80 seat 13 as previously mentioned will be engaged by the teeth 22 when the jaws are closed.

For the purpose of connecting the two 85 members of the device so as to permit of the aforesaid pivotal and longitudinal movement, the shank 10 has pivotally mounted thereon as shown at 23 a lever 24, while pivotally connected to this lever 24 as shown at 25 is an ear or lug 26 which extends from the shank 19 of the relatively 90 movable jaw. The opposite end of the lever 24 is shaped to provide a trigger 27.

The shanks 10 and 19 are connected by 95 springs 28 which are disposed upon opposite sides of the said shank.

After the device has become sufficiently heated, a quantity of hair is placed across the seat provided in the rigid jaw 12 and the jaw 21 is permitted to close upon this 100 hair, the springs 28 acting to hold the jaws in closed position. By pulling the trigger 105 27 with one finger of the hand which grasps the handle 11, the jaw 21 will be moved forward to the position shown in Figure 6 of the drawings, the springs 28 holding the jaws closed sufficiently tight to prevent reverse movement of the jaw 21. The shape 110 of the seat 13 and of the jaw 21 provides a wave in the hair in one direction, while a forward movement of the jaw 21 due to the teeth 18 and 22 will provide a wave in

another direction so that the Marcel wave effected is produced. By pressing inwardly upon the handle 20, the jaws may be separated as shown by the dotted lines in 5 Figure 6 and the hair released, the operation being then repeated.

The invention is susceptible to various changes in its form, proportions and minor details of construction and the right is 10 herein reserved to make such changes as properly fall within the scope of the appended claim.

Having described the invention what is claimed is:—

15 A curling iron of the character described comprising rigid and manipulating jaws respectively, a movable handle for said jaws, the handle being rigid for receiving therein conducting means for heating the rigid 20 jaw, said jaw being transversely curved and provides a longitudinally disposed seat

on the upper face thereof and spaced channels in the opposite face to receive an electric heating element connected to the current conducting means, a row of spaced 25 teeth struck up from the upper side of the transversely curved portions of the rigid jaw, the relatively movable jaw having a row of spaced teeth upon its underside and normally contacting the intermediately 30 curved portion of the rigid jaw which provides a seat therewithin, an apertured lug extending from the underside of the movable jaw handle, a lever pivoted intermediate of its length to the rigid jaw handle and its upper portion pivoted to the lug of the movable jaw handle, the lower portion of said lever providing a fingerhold and spring retractile means connected to both the handles. 35

JERROL E. LAWTON.
